(57) **CLAIM**

The ornamental design for a martial arts focus target in the shape of a face, substantially as shown and described.

DESCRIPTION

FIG. 1 is a perspective view of one form of the martial arts focus target in the shape of a face in accordance with the design of the invention showing the martial arts focus target in the shape of a face held in a hand (shown in broken lines) of an individual.

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings indicate structure and features that form no part of the claimed design. The broken line drawings of individual ring members are not part of the claimed design.
